(57) **CLAIM**

The ornamental design for a twisted probe cap, as shown and described.

DESCRIPTION

FIG. 1 is a rear-facing, top perspective view of a twisted probe cap showing our design;

FIG. 2 is a front-facing, top perspective view of the twisted probe cap of FIG. 1;

FIG. 3 is a front-facing, bottom perspective view of the twisted probe cap of FIG. 1;

FIG. 4 is a top view of the twisted probe cap of FIG. 1;

FIG. 5 is a bottom view of the twisted probe cap of FIG. 1;

FIG. 6 is a front view of the twisted probe cap of FIG. 1;

FIG. 7 is a rear view of the twisted probe cap of FIG. 1;

FIG. 8 is a right view of the twisted probe cap of FIG. 1; and,

FIG. 9 is a left view of the twisted probe cap of FIG. 1.

The broken lines represent both parts of the article as well as the boundaries of the claim. None of the broken lines form part of the claim.

1 Claim, 9 Drawing Sheets(56)
